Primary Examiner — Sandra S Snapp*Assistant Examiner* — Leisha N Price(74) *Attorney, Agent, or Firm* — Antoinette M. Tease(57) **CLAIM**

The ornamental design for a screw-type fencing staple, as shown and described.

DESCRIPTION

FIG. 1 is a top perspective view of a screw-type fencing staple showing the new design.

FIG. 2 is a bottom perspective view of a screw-type fencing staple showing the new design.

FIG. 3 is a right side view of a screw-type fencing staple showing the new design.

FIG. 4 is a left side view of a screw-type fencing staple showing the new design.

FIG. 5 is an environmental left side view showing the screw-type fencing staple in relation to a screw.

FIG. 6 is a front view of a screw-type fencing staple showing the new design.

FIG. 7 is a rear view of a screw-type fencing staple showing the new design.

FIG. 8 is a top plan view of a screw-type fencing staple showing the new design; and,

FIG. 9 is a bottom plan view of a screw-type fencing staple showing the new design.

The broken lines showing of the screw in FIG. 5 illustrate the environment of the claimed design and forms no part thereof.
